UNITED STATES PATENT OFFICE.

DAVID F. HAYNES, OF BALTIMORE, MARYLAND.

DESIGN FOR A COVERED DISH.

SPECIFICATION forming part of Design No. 22,155, dated January 24, 1893.

Application filed December 29, 1892. Serial No. 456,709. Term of patent 3½ years.

To all whom it may concern:

Be it known that I, DAVID F. HAYNES, a citizen of the United States, residing at Baltimore, Maryland, have invented and produced 5 a new and original Design for a Covered Dish, of which the following is a specification, reference being had to the drawings, forming a part hereof.

Referring to the said drawings, Figure 1 is 10 a perspective view of the covered dish, and Fig. 2 a top view of the same.

I describe the dish proper as follows:—The general form of the body A as seen from its top, is an irregular octagon. The sides *a a* 15 are longer than the ones *b b*, and the ones *c c* are shorter than the sides *b*. The sides are all formed of hollow lines and the corners or angles are rounded. Where the sides *c* join the other sides are slight depressions *d*. The 20 body as seen from the side has a lip *e* at the upper edge. Below this lip the body falls in in a regular curve *f*, and is then bulged out so as to be in alignment with the lip. It then falls inward and is connected by a curve or 25 fillet *g* to a slightly projecting beaded base *B*,

which corresponds very nearly in configuration with the upper edge or lip *e*, but smaller. The sides *a a* and *b b* have slightly projecting panels *h*.

C C are the handles having suitable scroll 30 work extending from the sides *b*. Around the body and on a line with the top of the panels is a narrow scroll *i* in relief. The lid D at its outer edge conforms in shape of outline with the base *B* and its sides are modifications of the sides of the body but reversed. The top of the lid is nearly flat, and has a handle *E* similar to those on the body, but 35 smaller. The lid has scroll work in relief which extends entirely around it which corresponds in character with the scroll-work on 40 the body.

I claim as my invention:—

The design for a covered dish as herein shown and described.

DAVID F. HAYNES.
